ERNEST JAMES SMITH, OF LONDON, ENGLAND, ASSIGNOR TO THE GOSS PRINTING PRESS COMPANY, A CORPORATION OF ILLINOIS

SHEET FOLDING AND DELIVERING MECHANISM

Application filed March 28, 1930. Serial No. 439,628.

The invention relates to new and useful improvements in sheet cutting, folding and delivering mechanisms, and more especially, in certain of its aspects, to such mechanisms especially capacitated for use with high speed 5 rotary printing presses.

Objects and advantages of the invention will be set forth in part hereinafter and in part will be obvious herefrom, or may be 10 learned by practice with the invention, the same being realized and attained by means of the instrumentalities and combinations pointed out in the appended claims.

The invention consists in the novel parts, 15 construction, arrangements, combinations and improvements herein shown and described.

The accompanying drawings, referred to herein and constituting a part hereof, illustrate one embodiment of the invention, and together with the description, serve to explain the principles of the invention.

Of the drawings—

Fig. 1 is a vertical section through a mechanism embodying the invention:

Fig. 2 is a fragmentary detail of the silencing means for the impaling pins;

Fig. 3 is an end elevation of the cylinders shown in Fig. 1 and showing also the folder 30 actuating cams and the star wheels of the deliveries:

Fig. 4 is a fragmentary top plan of the other ends of the cylinders shown in Fig. 3 and showing the pin cams and connected 35 mechanisms;

Figs. 5 and 6 are detached views of the interchangeable cam for actuating the impaling pin mechanisms; and

Figs. 7 and 8 are diagrammatic showings 40 of the operation of the two pin actuating cams.

The invention is directed to mechanism 45 capacitated to receive rapidly running webs, and to cut off therefrom sheets, or groups of sheets in the case of associated webs, and to fold off the sheets, or groups thereof optionally to a single delivery mechanism or to a plurality of such mechanisms. In either case, the mechanism, through alternate folding-off 50 action or through collection, effects a relative-

ly slow delivery of the folded-off products with respect to the speed of the web. In accordance with one feature of the invention, the entire product may be collected and folded off to a selected one of a plurality of delivery devices, or the mechanism may be run "straight" to fold off and deliver sequentially to said plurality of delivery devices. 85

One object of the invention is to provide mechanism having the alternative functions 60 described, wherein the different devices and groups of mechanisms are of developed and tested forms, conducing to simplicity and reliability of operation, thereby avoiding stoppages, breakages and other faults and defects as well as realizing the advantages already outlined. 65

In the exemplary and present preferred embodiment, two "three-way," cutting, collecting and folding cylinders coact together 70 to receive the web lead and to cut off the sheets therefrom in a known manner. The sheets are taken either alternately by the two cylinders, or in succession by one of them. In the latter case the other cylinder cooperates 75 only to cut off the sheets, the sheet-taking and folding-off mechanism thereof being silent. Either cylinder may be silent in the manner described, and in such case, when either cylinder is silenced (except for cutting), the other cylinder acts as a collecting and folding-off cylinder. 80

It will be understood that the foregoing general description, and the succeeding detailed description as well, are explanatory 85 and exemplary of the invention but are not restrictive thereof.

Referring now in detail to the embodiment 90 of the invention illustrated by way of example in the accompanying drawings, a suitable source of web supply is provided, and in the case of a rotary printing press, one or more four-page-wide perfected webs are centrally longitudinally slit, associated when 95 required, and are run over a pair of formers and thence to the sheet-cutting folding and delivery mechanism of the present invention. In the embodied form of the latter, two cylinders 1 and 9 cooperate together, the web 100

being fed between these cylinders from the formers or other mechanisms. The cylinder 1 is fixed on a shaft 2, journaled in bearings 3 in the respective side frames 4 of the machine. The cylinder 9 is fixed on a shaft 10, journaled in bearings 8 in the machine frame. These two cylinders, as embodied, are "three-way cylinders", that is, there is space for three sheets, or groups of sheets, circumferentially about each of the cylinders. The cylinder 1 is provided with three sheet-cutting devices 3, 4 and 5, corresponding to the sheet-supporting spaces upon the cylinder. The cylinder 9 is supplied with three cooperating sheet-cutting devices 11, 12 and 13, spaced apart in the same manner. These sheet-cutting devices cooperate together as the cylinders rotate to cut the sheets from the web or webs.

Sheet-taking, holding and releasing means are provided on both cylinders, and these are arranged and coat so that either each successive lead of the web may be taken by one cylinder, or by the other cylinder, the corresponding sheet-taking devices on the idle cylinder being silenced during this operation; or, the sheet taking, folding and delivering devices upon the two cylinders may be set to operate alternately, the lead of the web being taken first about one cylinder, and after the sheet, or group of sheets, is cut from the web, the new lead of the web is carried about the other cylinder. That is, either cylinder may be run collect while the other is silent, except for the sheet cutting; or, alternate sheets, or groups, are cut and one is taken in one cylinder, and the next sheet or group is taken by the other cylinder. In any of the cases, the delivery runs at half speed proportionately to the web.

As embodied, cylinder 1 is provided with three sets of impaling pins 16, 17 and 18, arranged adjacent to and in cooperative relation with the sheet-cutting devices 3, 4 and 5. The pins 16 are mounted on arms 21, fixed on a shaft 22, journaled in the cylinder, one end of the shaft projecting from the cylinder. Fixed to said projecting end of the shaft is an arm 23, on which is mounted a roller 24, which runs in a rotatable cam 25. Cam 25 is fixed to a gear 26 by bolts 31, the gear being journaled loosely on shaft 2. The pins 17 are mounted upon, and are actuated from the cam 25 by a similar mechanism, the parts being correspondingly numbered with an added *a*. The pin cam mechanism 18 is likewise similarly constructed, mounted and operated, the parts being similarly numbered with an added *b*. In the embodied form of silencing device, which is applied to all of the impaling pin mechanism, the arm 23 has a tail 27 projecting oppositely from the shaft 22, and this in face contact with a plate 28 fixed to the shaft. These two are connected together by a bolt and slot connection 29, whereby the

arm 23 may be positioned so that the impaling pins may be projected and retracted by the cam 25 or may have their entire movement within the cylinder, that is, always in retracted relation.

Means are provided according to one feature of the invention whereby either cylinder may be run collecting while the other cylinder operates only as a coacting cutting cylinder. Accordingly, each of the impaling pin mechanisms is connected with means whereby any set of pins is either projected each time it passes the sheet cutting and taking position, or is projected only on every alternate passing thereof. The pins are also retracted at the folding-off position, either on every revolution of the cylinder or on every other revolution thereof, in harmony with the sheet-taking action of the pins. In the embodied form of such means, two interchangeable rotating cams 25*a* and 25*b* are provided, having their cam tracks differently shaped to effect the desired functions as described. Both cams are split, as shown in Figs. 5 and 6, whereby they are interchangeable with relation to the shaft 2 and the gear wheel 26, the halves being held together and to the gear wheel by bolts 31. The manner of operation of the respective cams will be described later herein.

In the embodied form of folding means, medianly positioned with respect to the three series of impaling pins are three folding mechanisms 41, 42 and 43. The mechanism 41 comprises a carrier 45, to which is fixed a single folding blade 46, the carrier being mounted on a shaft 47, journaled on the cylinder, one end of the shaft projecting beyond the cylinder. Fixed to the projecting end of shaft 47 is a cross arm 51, in the ends of which are mounted cam rollers 52 and 53, which run on a cam ring or track 54, mounted in fixed position upon the machine frame. The folder actuating device is of the general Husby cam type, comprising a rotating disc 57, rotatably mounted at 58 upon the machine frame. The cam disc is provided with two tangentially-disposed slots 59 and 60, into and out of which the cam rollers run to impart the semi-rotation to shaft 47 during the folding operation. The disc 57 is provided with a gear wheel 63, which intermeshes with a gear wheel 64, fixed on the shaft 2. The product is folded off from the cylinder between two folding-off rollers 65 and 66 and conveyed to a suitable delivery mechanism, shown as comprising a star wheel 67 fixed on a shaft 68. The star wheel may lay the papers upon a delivery belt of the usual, or any other suitable type.

The folding device 42 comprises a carrier 71 carrying a single folding blade 72, the carrier being fixed on a shaft 73 journaled upon the cylinder and with one end projecting beyond the cylinder. Fixed to the

projecting end of shaft 73 are cross arms 74, in the ends of which are mounted cam rollers 75 and 76, which run upon the ring cam 54. In like manner the folding device 43 comprises a carrier 81, mounted on which is a single folding blade 82, the carrier being fixed on a shaft 83, which is journaled on the cylinder. Fixed to the projecting end of shaft 83 is a cross arm 84, journaled in which are a pair of cam rollers 85 and 86, running on the cam track 54.

Referring now to cylinder 9, which is equipped with similar sheet taking, holding and releasing devices, there are shown three sets of impaling pins 91, 92 and 93, mounted in cooperative relation with the sheet-cutting devices 11, 12 and 13 of this cylinder. The pins 91 are mounted on arms 97, fixed on a shaft 98, journaled in the cylinder heads, one end of the shaft projecting therefrom. To the projecting end of the shaft is fixed an arm 99, in which is journaled a cam roller 100, which runs in a cam 101. The pin mechanism 92 is similarly constructed and has the same reference numerals applied thereto with *a* added. The pin mechanism 93 is likewise of similar construction and has the same reference numerals applied thereto with an added *b*. These are both likewise actuated by cam 101. Cam 101 is fixed to a gear wheel 102, loosely journaled on the shaft 10 of cylinder 9. Cam 101 is an interchangeable cam, similar to cam 25, and is mounted on its gear wheel in like manner. Figs. 5 and 6 will serve also to illustrate cam 101. Gear wheel 26 for cam 25 of cylinder 1, and gear wheel 102 for cam 101 of cylinder 9 intermesh and rotate one for one, and are driven by suitable mechanisms later to be described.

In the embodied folding means, medianly positioned with reference to the sheet carrying surfaces of the cylinder 9 are three folding devices 111, 112 and 113. The device 45 111 is provided with a carrier 115, on which is mounted a single folding blade 16, the carrier being fixed on a shaft 117, journaled on the cylinder and having one end thereof projecting beyond the cylinder. To said projecting end of shaft 117 is fixed across arm 118, in the ends of which are journaled cam rollers 119 and 120, running on the circular cam track 121, mounted in fixed position upon the machine frame.

The folding device 112 is of similar construction, having a carrier 131 having a single folding blade 132, fixed on a shaft 133, journaled on the cylinder. A cross arm 134 is fixed on the projecting end of shaft 133, and cam rollers 135 and 136 are journaled in the ends of the cross arm and run upon the ring cam 121. Folding device 113 has a carrier 139 provided with a single folding blade 140, the carrier being fixed on the shaft 141, journaled on the cylinder, and to the

projecting end thereof is fixed a cross arm 142, in the ends of which are journaled cam rollers 143 and 144, likewise running on the ring cam 121. The actuating mechanism for this folder comprises the rotary disc 151 rotatably mounted at 152 upon the machine frame, the disc being provided with tangentially-disposed cam slots 153 and 154. The cam is fixed to a gear 155, which meshes with a gear 156, fixed on the shaft 10 of cylinder 75 9. The product is folded off to folding rollers 161 and 162 and delivered to a delivery mechanism shown as comprising a star wheel 163, which may deliver to the usual form of delivery belt or any other suitable construction.

In the embodied form of driving means for the pin-actuating cams 25 and 101, gear wheel 26 of the intermeshing gears 26 and 102 meshes with a gear wheel 171, fixed on a shaft 172, journaled in the side frame 4 and in a bracket 175. Fixed also to shaft 172 is a gear wheel 176, which meshes with a gear wheel 177, fixed on the shaft 2 of cylinder 1. Fixed on shaft 2 is a gear wheel 178, which meshes with a gear wheel 179 fixed on the shaft 10 of cylinder 9, and rotating in one-to-one relation. The rotation of the cams 25 and 101 to their respective cylinders 1 and 9 is in the ratio of three to two, and in the same direction. The gears may be proportioned in any desired manner to effect this, and as shown they are in the following ratio:—

$$\frac{177}{176} \times \frac{171}{26} = \frac{3}{1} \times \frac{1}{2} = \frac{3}{2},$$

which gives the desired ratio.

As stated, the shape of the cam tracks for either cylinder 1 or 9 is changed whenever the particular cylinder is to be run either straight or collect. When either of the cylinders is run collect, the impaling pins on the other cylinder are silenced by means of the respective bolt and slot connections 29.

In the operation of the mechanism, and considering either cam 25*a* or 101, and the both cylinders as on a "straight run" (Figs. 1, 5 and 7), the cam makes three revolutions to two revolutions of cylinder 1 and in the same direction. Impaling pins A (which may be any given set of pins) are in the projected position and take the web lead at *x* on the cam. The pins A then rotate 150° to the point Y, where they are retracted into the cylinder to release the sheets, which at that instant are cut off and folded into the folding-off rollers 65 and 66. The low point L on the cam, which is 75° behind the pins A, when in the position of Fig. 7 (that is, when taking the web lead), rotates 225° while the pins A are rotating 150° from *x* to *y* (that is, from sheet-taking to sheet-releasing positions), and thereby the cam roller M for the pins A and the low L on the

cam coincide at Y and the pins are retracted, thereby releasing the sheets as they are folded off.

When the set of pins B are at position A, they must be retracted within the cylinder, as the lead of the web is then taken by the impaling pins on cylinder 9. The rotation of pins B from the position of Fig. 7 to position A is 120° , and during this rotation of pins B, the cam rotates 180° from the position of Fig. 7, and this puts the low side of the cam at position A, and pins B are thereby retracted within the cylinder and do not take the web lead.

When pins C have reached position A, they must project, as cylinder 1 again takes the web lead as was the case with pins A. The rotation of the pins from their position in Fig. 7 to position A is 240° , and during this rotation the cam rotates 360° (and is thus again in the position shown in Fig. 7), and pins C are projected and take the lead of the web. The entire cycle then repeats with the pins C, in the manner already described with relation to pins A, and later the same thing occurs with respect to the pins B. Thus, every alternate time the web lead is taken by cylinder 1 and on the other time by cylinder 9, the folding-off occurring as has already been described.

Considering now the machine as set for collecting by cylinder 1, the interchangeable split cam shown in Fig. 5 has been replaced by the cam shown in Figs. 6 and 8. The cam, of course, still makes three revolutions to two revolutions of the cylinder 1, and in the same direction as the cylinder. In the position shown in Fig. 8, the pins A are projected and take the lead end of the web, the corresponding sheet-taking surface having come up to this position bare after the collected product has been folded off. At this time pins B have one sheet or group, and will take another sheet or group thereon when position A is reached. The pins C are just about to release the collected product at the instant of folding-off.

Pins A are projected at position A of Fig. 8, and must stay out during one complete rotation of cylinder 1, to impale the web lead which is just being taken in Fig. 8 and to then again impale the web lead to collect the second sheet or group upon the first, and must remain out until point Y is reached, where the pins must be retracted to release the collected product at the instant of folding-off. The complete rotation of the pins A from the point of taking the first web lead, past the taking of the second web lead, and to the position Y with the collected product is 510° , and the cam rotates during this time 765° . Thus the low part L of the cam and the actuating roller for the pins A coincide at the point Y, and thereby the pins A are retracted, and the collected product folded off.

Pins B must project beyond the cylinder until they reach point A to take the second web lead to complete the collection of the two products, and must continue projected until they reach the point Y. At that point they must be retracted within the cylinder to release the collected product at the instant of folding-off. The rotation of pins B from the position shown in Fig. 8, to the point Y is 270° , and during the same time the cam rotates from the position shown in Fig. 8, through 405° , which brings the low L of the cam to the point Y coincidentally with the actuating roller for the pins B, which are retracted and the collected product is folded off.

Pins C must rotate from the position shown in Fig. 8 through 30° to the point Y, and during that time the low point L on the cam rotates 45° , which brings them together at Y, and the pins C, are retracted, and the collected product is folded off. The sequence then begins again with pins A.

It will be understood that the plates will be positioned on the opposite halves of the form cylinders of the various printing couples so as to get a properly folded product at either delivery.

The invention in its broader aspects is not limited to the specific mechanisms shown and described but departures may be made therefrom within the scope of the accompanying claims without departing from the principles of the invention and without sacrificing its chief advantages.

What I claim is:—

1. A sheet folding and delivering mechanism including in combination two coating cylinders each provided with a plurality of sheet holding and releasing devices and a plurality of folding devices, a plurality of delivery devices, and means whereby the total folded products may be delivered either to one or a plurality of the delivery devices.

2. A sheet folding and delivering mechanism including in combination two coating cylinders each provided with a plurality of sheet holding and releasing devices and a plurality of folding devices, a plurality of delivery devices, and means whereby the total sheets supplied may be folded by one of said cylinders or alternately by both.

3. A sheet folding and delivering mechanism including in combination two coating cylinders each provided with a plurality of sheet holding and releasing devices and a plurality of folding devices, a plurality of delivery devices, and means whereby the total sheets supplied may be folded by either of said cylinders or alternately by both.

4. A sheet folding and delivering mechanism including in combination two coating cylinders each provided with a plurality of sheet taking and releasing devices and a plurality of folding devices, and means for

silencing the sheet taking and releasing means on one of said cylinders folding rollers coacting with the folding means of one of the cylinders and folding rollers coacting with the folding means of the other cylinder.

5. A sheet folding and delivering mechanism including in combination two coacting cylinders each provided with a plurality of sheet taking and releasing devices and a plurality of folding devices, and means for silencing the sheet taking and releasing means on either of said cylinders, folding rollers coacting with the folding means of one of the cylinders and folding rollers coacting with the folding means of the other cylinder.

6. A sheet folding and delivering mechanism including in combination two coacting cylinders each provided with sheet taking and releasing devices and folding devices, and means for silencing the sheet taking and releasing means, on either of said cylinders, folding rollers coacting with the folding means of one of the cylinders and folding rollers coacting with the folding means of the other cylinder.

7. A sheet folding and delivering mechanism including in combination two coacting cylinders each provided with a plurality of sheet taking and releasing devices and a plurality of folding devices, and means for silencing the sheet taking and releasing means and folding means on one of said cylinders, folding rollers coacting with the folding means of one of the cylinders and folding rollers coacting with the folding means of the other cylinder.

8. A sheet folding and delivering mechanism including in combination two coacting cylinders each provided with a plurality of sheet taking and releasing devices and a plurality of folding devices, and means for silencing the sheet taking and releasing means and folding means on either of said cylinders, folding rollers coacting with the folding means of one of the cylinders and folding rollers coacting with the folding means of the other cylinder.

9. A sheet folding and delivering mechanism including in combination two coacting cylinders each provided with sheet taking and releasing devices and folding devices, and means for silencing the sheet taking and releasing means and folding means on either of said cylinders, folding rollers coacting with the folding means of one of the cylinders and folding rollers coacting with the folding means of the other cylinder.

10. A sheet folding and delivering mechanism including in combination two coacting cylinders, provided with an equal number of sheet taking and releasing means and an equal number of folding devices, and means whereby the total folded products may be de-

livered from one or from both of said cylinders.

11. A sheet folding and delivering mechanism including in combination two coacting cylinders, provided with an equal number of sheet taking and releasing means and an equal number of folding devices, a plurality of delivery devices, and means whereby the total folded products may be delivered to one or both of said folders.

12. A sheet folding and delivering mechanism including in combination two coacting cylinders, provided with an equal number of sheet taking and releasing means and an equal number of folding devices, means for silencing the sheet taking and releasing means on one of said cylinders, and means for receiving the folded off products.

13. A sheet folding and delivering mechanism including in combination two coacting cylinders, provided with an equal number of sheet taking and releasing means and an equal number of folding devices, means for silencing the sheet taking and releasing means on either of said cylinders and means for receiving the folded off products.

14. A sheet folding and delivering mechanism including in combination two coacting cylinders provided with an equal number of sheet taking and releasing means and an equal number of folding devices, a pair of folding off rollers cooperating with one of said cylinders, a pair of folding rollers cooperating with the other cylinder, and means for silencing the sheet taking and releasing means on one of said cylinders.

15. A sheet folding and delivering mechanism including in combination two coacting cylinders provided with an equal number of sheet taking and releasing means and an equal number of folding devices, a pair of folding off rollers cooperating with one of said cylinders, a pair of folding rollers cooperating with the other cylinder, and means for silencing the sheet taking and releasing means on either of said cylinders.

16. A sheet folding and delivering mechanism including in combination two coacting cylinders each provided with a plurality of sheet holding and releasing devices and a plurality of folding devices, coacting sheet cutting devices on said cylinders, a plurality of delivery devices, and means whereby the total folded products may be delivered either to one or a plurality of the delivery devices.

17. A sheet folding and delivering mechanism including in combination two coacting cylinders each provided with a plurality of sheet holding and releasing devices and a plurality of folding devices, coacting sheet cutting devices on said cylinders, a plurality of delivery devices, and means whereby the total sheets supplied may be folded by one of said cylinders or alternately by both.

18. A sheet folding and delivering mecha-

- nism including in combination two coacting cylinders each provided with a plurality of sheet taking and releasing devices and a plurality of folding devices, and means for silencing the sheet taking and releasing means on one of said cylinders, coacting sheet cutting devices on said cylinders, folding rollers coacting with the folding means of one of the cylinders and folding rollers coacting with the folding means of the other cylinder.
19. A sheet folding and delivering mechanism including in combination two coacting cylinders each provided with a plurality of sheet taking and releasing devices and a plurality of folding devices, and means for silencing the sheet taking and releasing means on either of said cylinders, coacting sheet cutting devices on said cylinders, folding rollers coacting with the folding means of one of the cylinders and folding rollers coacting with the folding means of the other cylinder.
20. A sheet folding and delivering mechanism including in combination two coacting cylinders each provided with sheet taking and releasing devices and folding devices, and means for silencing the sheet taking and releasing means on either of said cylinders, coacting sheet cutting devices on said cylinders, folding rollers coacting with the folding means of one of the cylinders and folding rollers coacting with the folding means of the other cylinder.
21. A sheet folding and delivering mechanism including in combination two coacting cylinders each provided with a plurality of sheet taking and releasing devices and a plurality of folding devices, and means for silencing the sheet taking and releasing means and folding means on one of said cylinders, coacting sheet cutting devices on said cylinders, folding rollers coacting with the folding means of one of the cylinders and folding rollers coacting with the folding means of the other cylinder.
22. A sheet folding and delivering mechanism including in combination two coacting cylinders, provided with an equal number of sheet taking and releasing means and an equal number of folding devices, coacting sheet cutting devices on said cylinders, and means whereby the total folded products may be delivered from one or from both of said cylinders.
23. A sheet folding and delivering mechanism including in combination two coacting cylinders, provided with an equal number of sheet taking and releasing means and an equal number of folding devices, coacting sheet cutting devices on said cylinders, means for silencing the sheet taking and releasing means on one of said cylinders, and means for receiving the folded off products.
24. A sheet folding and delivering mechanism including in combination two coacting cylinders provided with an equal number of

sheet taking and releasing means and an equal number of folding devices, coacting sheet cutting devices on said cylinders, a pair of folding off rollers cooperating with one of said cylinders, a pair of folding rollers cooperating with the other cylinder, and means for silencing the sheet taking and releasing means on one of said cylinders.

25. A sheet folding and delivering mechanism including in combination two cooperating cylinders, sheet taking and releasing means on said cylinders, folding devices on said cylinders, folding off rollers cooperating with each of said cylinders, the folding means folding off sheets once in a plurality of passages of the folding rollers.

26. A sheet folding and delivering mechanism including in combination two cooperating cylinders, sheet taking and releasing means on said cylinders, folding devices on said cylinders, folding off rollers cooperating with each of said cylinders, the folding means on said cylinders folding off the sheets from the cylinder in alternate relation.

27. A sheet folding and delivering mechanism including in combination two cooperating cylinders, sheet taking and releasing means on said cylinders, folding devices on said cylinders, folding off rollers cooperating with each of said cylinders, the folding means folding off sheets once in a plurality of passages of the folding rollers and the folding devices on the two cylinders folding off in alternate relation.

28. A sheet folding and delivering mechanism including in combination two cooperating cylinders, sheet taking and releasing means on said cylinders, folding devices on said cylinders, means for silencing the sheet taking and releasing means on a cylinder, folding off rollers cooperating with each of said cylinders, the folding means folding off sheets once in a plurality of passages of the folding rollers.

29. A sheet folding and delivering mechanism including in combination two cooperating cylinders, sheet taking and releasing means on said cylinders, folding devices on said cylinders, means for silencing the sheet taking and releasing means on a cylinder, folding off rollers cooperating with each of said cylinders, the folding means folding off sheets once in a plurality of passages of the folding rollers.

30. A sheet folding and delivering mechanism including in combination two cooperating cylinders, sheet taking and releasing means on said cylinders, folding devices on said cylinders, means for silencing the sheet taking and releasing means on either cylinder, folding off rollers cooperating with each of said cylinders, the folding means folding off sheets once in a plurality of passages of the folding rollers.

31. A sheet folding and delivering mecha-

cylinders, sheet taking and releasing devices and folding devices on each cylinder, and a pair of folding off rollers for each of said cylinders and means for selectively silencing some of the sheet taking and releasing means.

44. A sheet folding and delivering mechanism including in combination two three way cylinders, cooperating sheet cutting means on said cylinders, sheet taking and releasing devices and folding devices on each cylinder, and a pair of folding off rollers for each of said cylinders.

45. A sheet folding and delivering mechanism including in combination two cooperating cylinders, sheet taking and releasing means on said cylinders, a pair of folding off rollers for each of said cylinders, sheet folding means cooperating therewith, and means for selectively silencing some of the sheet taking and releasing means.

46. A sheet folding and delivering mechanism including in combination two cooperating cylinders, cooperating sheet cutting means on said cylinders, sheet taking and releasing means on said cylinders, a pair of folding off rollers for each of said cylinders, sheet folding means cooperating therewith, and means of selectively silencing some of the sheet taking and releasing means.

47. A sheet folding and delivering mechanism including in combination two cylinders having cutting devices cooperating together to cut sheets from webs, impaling pins on either cylinder at the respective cutting devices, and devices for actuating said impaling pins alternately at the sheet cutting point to direct the successive cuts of sheets alternately on the two cylinders, or to silence the pins on one cylinder and cause those on the other cylinder to take successive cuts of sheets from the web.

48. A sheet folding and delivering mechanism including in combination two cylinders each having an uneven number of sheet carrying surfaces thereon and a sheet cutting device for each of those surfaces cooperating with a similar device on the other cylinder to cut sheets from the web, sets of impaling pins for each of said sheet carrying surfaces, and devices for causing a set of impaling pins on one cylinder to take the web lead as a sheet is cut from the web and for causing the next succeeding set of impaling pins on the other cylinder to take the next web lead when the next sheet cut is made.

49. A sheet folding and delivering mechanism including in combination two cylinders each having an uneven number of sheet carrying surfaces thereon and a sheet cutting device for each of those surfaces cooperating with a similar device on the other cylinder to cut sheets from the web, set of impaling pins for each of said sheet carrying surfaces, and devices for causing a set of impaling pins on

one cylinder to take the web lead as a sheet is cut from the web and for causing the next succeeding set of impaling pins on the other cylinder to take the next web lead when the next sheet cut is made, or to actuate the sets of pins on one cylinder to take each successive web lead and to silence all the sets of pins on the other cylinder.

In testimony whereof, I have signed my name to this specification.

ERNEST JAMES SMITH.
